DESIGN FOR A GAME BOARD

Daniel C. Alexander, Paris, Mo.

Application March 31, 1942, Serial No. 106,412

Term of patent 7 years

To all whom it may concern:

Be it known that I, Daniel C. Alexander, a citizen of the United States, residing at Paris, in the county of Monroe and State of Missouri, have invented a new, original, and ornamental Design for a Game Board, of which the following is a specification, reference being had to the accompanying drawing, forming part thereof.

Figure 1 is a plan view of a game board in folded position; and

Figure 2 is a plan view thereof in open position, showing my new design.

Figure 3 is an edge elevational view.

I claim:

The ornamental design for a game board, as shown.

DANIEL C. ALEXANDER.
